UNITED STATES PATENT OFFICE.

ALBERT V. SAMMIS, OF HUNTINGTON, NEW YORK, ASSIGNOR TO FIRE GUN MANUFACTURING COMPANY, OF HUNTINGTON, NEW YORK, A CORPORATION OF NEW YORK.

LIQUID-PROJECTING DEVICE.

Application filed July 24, 1915. Serial No. 41,650.

To all whom it may concern:

Be it known that I, ALBERT V. SAMMIS, a citizen of the United States, and resident of Huntington, in the county of Suffolk and State of New York, have invented certain new and useful Improvements in Liquid-projecting Devices, of which the following is a specification.

My invention relates to devices for expelling and projecting liquids contained in receptacles, and particularly to devices by means of which the liquid will be expelled from the receptacle forcibly so as to be projected a considerable distance, as may be desirable in the case of portable fire extinguishers containing a fire-extinguishing liquid. The purpose of my invention is to provide a device of this character which will be simple and effective in operation, and by 20 means of which I am enabled to expel and project the liquid in a practically continuous stream or jet.

Three embodiments of my invention are shown in the accompanying drawings in 25 which—

Figs. 1 and 2 are vertical sections, looking in the same direction, and taken in the main through the center of the receptacle, but showing most of the interior parts in face view; Fig. 1 differs from Fig. 2 by showing the upper intake tube broken off and in a different position, also by showing the handle in operating position, while Fig. 2 shows the handle folded down and in section; the air-valve is omitted from Fig. 1, but is shown in section in Fig. 2; the guides 57, 58 appearing in Fig. 2 are omitted from Fig. 1, which shows the parts 57', 58' in section, as well as the nozzle 25'; Fig. 3 is substantially a central section of the apparatus, taken at right angles to the direction in which Fig. 1 faces, and showing all the interior parts in face view, with the exception of the guides 57, 58, which appear in section. Fig. 4 is a horizontal section taken on line 4—4 of Fig. 2; Fig. 5 is a partial vertical section through the lower part of the receptacle and projecting device; Fig. 6 is a vertical section through the upper part of my device; Figs. 7 and 8 are horizontal sections taken on lines 7—7 and 8—8 respectively of Fig. 6; Fig. 8^a

is a vertical section on line 8^a—8^a of Fig. 8; Fig. 9 is an outside view of certain parts shown in Fig. 6; Figs. 10 and 11 are sections corresponding to Figs. 7 and 8, but showing certain parts in a different position; Fig. 12 is a perspective view of one of the valve members shown in Figs. 6 and 8 (these valve members having been omitted from Fig. 11 for the sake of clearness); Fig. 13 is a detail vertical section showing certain valves; Fig. 14 is a horizontal section on line 14—14 of Fig. 13; Fig. 15 is a detail vertical section of another valve; Fig. 15^a is a horizontal section on line 15^a—15^a of Fig. 15; Fig. 16 is a top view showing the device hung against a wall; Fig. 17 is an enlarged view similar to Fig. 6, but with certain parts in the position shown in Figs. 10 and 11; this view also illustrates a modification of the 70 automatic air inlet; Figs. 18 and 19 are a vertical and a horizontal section respectively of a modification of my invention, Fig. 19 being taken on line 19—19 of Fig. 18.

In the said drawings, 20 indicates the 75 cylindrical wall of a receptacle whose ends are closed by heads 21 and 22. Through the head 21, at a point as near its periphery as possible, extends, rigidly connected therewith, a casing 23 to the lower portion of 80 which is secured rigidly the upper end of a pump cylinder 24. The lower end of said pump cylinder is closed by a plug 25 (Fig. 5), whose main portion rests on the head 22 of the receptacle, while a lateral extension 85 projects through said head and is perforated to form a nozzle 25' through which the fluid contained in the receptacle is expelled. The upper portion of the casing 23 receives another plug 26 held against longitudinal 90 movement by a shoulder on said casing and by an annular flange 27' on a cap 27, but is capable of turning around the axis of the pump cylinder. A washer 27'' is interposed 95 between the flange 27' and the corresponding portion of the plug 26 as well as the upper end of the casing 23, in order to insure a tight joint. The casing 23 and cap 27 are secured to the head 21 by screws 23', a washer 21' being preferably interposed between the head and the said cap. The head 100 is formed with a boss 21'' having flat upper

and lower surfaces. Through an axial hole in the plug 26 extends loosely a piston rod 28 carrying at its lower end the piston 29 adapted to reciprocate in the pump cylinder. 5 The upper end of the piston rod 28 is screwed into, or otherwise rigidly secured to, a head 30 to which is pivotally connected, by a pin 32', the shank 32' of a handle 32 by means of which the pump is operated. 10 A suitable packing 33 held in place by a gland 34 insures a tight joint between the piston rod 28 and the plug 26.

The plug 26 is formed with two segmental compartments 26', 26'' communicating with each other by channels 26* (Fig. 8a) which form a chamber or passage with said compartments. Each of these segmental compartments contains a U-shaped valve 35 (Fig. 12) capable of a slight longitudinal movement to cause its transverse central member to uncover a port 26^a in the lower portion of the plug 26, through which ports the passage 26', 26'', 26* may at times communicate with the chamber of the pump cylinder between the piston 29 and the plug 26. The vertical edges of the parallel longitudinal end members of the valves 35 are in guiding engagement with the inner wall of the casing 23 and with vertical surfaces 26^b on the inner portion of the plug 26. These longitudinal members also limit the opening movement of the valve. Between the segmental compartments 26', 26'' the plug 26 is provided with suitable recesses to receive sealing plugs 36, 36' which may be pressed outward by springs 37, 37' (Fig. 11) or they may be simply made of elastic material such as cork, in which case no separate springs are required (Fig. 8). These plugs 36, 36' are adapted to close the ends of tubes 38, 39 leading to diametrically opposite points of the said chamber of the plug 26. The said tubes extend to points near the bottom of the receptacle 20, the tube 38, which acts as an outlet tube, being connected with the nozzle 25', while the tube 39 communicates with the lower chamber of the pump cylinder at its bottom. The tube 39 consists of two parts between which is interposed a valve casing 40 containing a check valve the transverse central member 40' of which controls the passage of the fluid by opening or closing the port of the valve casing, while the longitudinal members 40'', of which there are three in the particular construction shown, serve to guide the valve in its movement toward and from its seat, and also to limit the opening movement of the valve.

From a point adjacent the lower end of the tube 39, another tube, 41, leads from the lowermost portion of the pump cylinder to a point slightly below the lower face of the plug 26. This tube 41 also consists of two parts connected by a valve casing 42, which latter contains two chambers 42', 42'' com-

municating with each other by a passage 42*. The ends of this passage form ports adapted to be closed by the central transverse member 43 or 44 of suction valves adapted to become seated on said ports, said 70 valves also having longitudinal members 43', 44' respectively (four as shown) which not only guide the valve in its opening or closing movement, but also limit the extent of its opening movement. From the passage 75 42* a short tube 45 leads to a similar passage 46* of a valve casing 46 having two chambers 46', 46'' and containing two ball-valves 47, 47' with a guide rod 48 connecting them. The valve chambers 46', 46'' communicate with tubes 49, 50 respectively which extend in opposite directions from the casing 46 lengthwise of the receptacle, the free end of the tube 49 reaching to a point adjacent the head 21 of the receptacle, while the free end of the tube 50 reaches to a point adjacent the other head 22 of the receptacle. The connection between the tubes 49, 50 and the valve casing 46 is not a rigid one, but loose and preferably universal, so as to allow the free ends of the tubes 49, 50 to assume a lowermost position adjacent to the heads of the receptacle. These tubes, which are rigid, have their attached ends extended into or through ball-shaped members 49', 50' 90 respectively, which are held loosely within the valve chambers 46' and 46'' by caps 51, 52 respectively, recessed to fit the said ball-shaped members 49', 50'. In order to prevent any longitudinal movement of the ball-shaped members 49', 50' with their respective tubes 49, 50, and to insure a tight joint, perforated disks 53, 54 are provided within the valve chambers; these disks have recessed seats for the ball-shaped members and are 100 pressed against the latter by springs 55, 56 respectively. This will allow the ball-shaped members a certain freedom of movement around their centers, yet prevent any leakage past their outer surfaces. The tubes 110 49, 50 are preferably weighted at or near their free ends, as shown at 49'', 50'' so as to make sure that these free ends or intakes, or at least one of them, will always assume a position lowermost in the receptacle, irrespective of the position in which the receptacle is being held and operated. In order to insure these swinging ends of the tubes 49, 50 against getting caught and wedged between the other tubes within the 120 receptacle, I provide guides 57, 58 (Figs. 2, 3 and 4) secured to the pump cylinder by flanges 57', 58'. These guides are arranged in such a way that the tubes 49, 50 will slide on them to the lowest point in the receptacle and cannot become caught in other parts of the device. This of course applies only to cases where the receptacle is held and operated in such a position that the pump cylinder and connected tubes will be 130

located below the remaining space of the receptacle. In all other positions the free ends of the tubes 49, 50, or at least one of them, will slide along the cylindrical wall 5 of the receptacle so as to bring the inlet of the active tube to the lowermost point of the receptacle.

In the example of my invention illustrated in the drawings, I have shown the 10 heads of the receptacle as being of spherical curvature, with the centers of curvature lying in the axis of the receptacle. This gives the receptacle a symmetrical shape and appearance. In this case, the points about 15 which the intake tubes swing, that is the centers of the ball-shaped members 49', 50', will also lie in the axis of the receptacle. However, the symmetrical arrangement is not essential to my invention, the above advantage being present as long as the heads 20 of the receptacle are spherically curved, with the centers of the curvature coinciding with the centers of the swinging movement of the respective intake tubes, so that the intake 25 ends of the tubes 49, 50 will always be at the same distance from the heads of the receptacle (as near to them as practicable) in whatever position the receptacle may be held.

The head or top 21 of the receptacle is 30 provided with a filling opening normally closed by a cap 59, which, in the preferred form of my invention, also contains an automatic air valve 59' of any approved construction, through which air will be drawn 35 into the receptacle whenever liquid is expelled therefrom. The cap 59 is shown as a wing screw adapted to receive between its two wings the shank 32' of the folding handle 32, when the apparatus is not being used. 40 The wings may be provided with suitable holes so that the handle can be tied to the wing screw and sealed thereto if desired. In order to bring the handle into the operative position, it will be swung on its pivot, 45 the pin 32'', until its shank is in alignment with the head 30. A sleeve 60 surrounding the shank 32' will then be pushed down by a spring 61 over the forked upper portion 50 of the head 30 and will firmly lock the handle to said head. After the apparatus has been used, the sleeve 60 may be pushed up 55 against the tension of the spring 61 until it clears the upper edge of the head 30, and the handle can then be swung on its pivot until 60 its shank rests on the wing screw 59. When folded as in Fig. 2, the handle is less exposed to injury say during shipment than when swung into the operating position (Figs. 1 and 3).

65 For the purpose of insuring the piston and the head 30 against accidental longitudinal movement, the following locking device is provided: The head 30 has at its lower portion two segmental ribs or flanges 30' located diametrically opposite each

other, each flange having at one end an outward projection or stop 30'', as shown in Figs. 7, 9 and 10. These flanges, which are preferably slightly beveled on their upper faces at the end opposite to the stop (Fig. 70 9), are adapted to be engaged from above by stationary segmental flanges 27* formed on the cap 27, on opposite sides thereof. In order to lock the head 30 against longitudinal movement, the handle 32 is pushed in 75 fully to the position shown in Figs. 7 and 9 and is then given a turn of about 90°, taking with it the head 30; that is, the handle will be turned until the stops 30'' engage the edges 27^a on the flanges 27* (Figs. 10 and 80 17). The head 30 with the piston rod and piston will thus be securely locked against longitudinal movement. The slightly beveled ends of the flanges 30' will facilitate the entrance of said flanges between the 85 flanges 27* and the flanges 27'. A felt washer 31 is interposed between the lower face of the head 30 and the upper face of the plug 26, so that in the locked position the head 30 will be pressed against the 90 flanges 27*. If it is desired to unlock the head 30, the handle 32 will be turned back to the position Figs. 7 and 9, the stops 30'' preventing the head 30 from being turned 95 too far. The flanges 30' will then have cleared the flanges 27* completely, and the pump can be operated readily (Figs. 6, 7 and 9).

The following device is employed to cause 100 the plug 26 to turn with the head 30 when the latter is in its lowermost position. The valve casing 26 is provided at diametrically opposite points with projections or flanges 26^a extending upwardly between the head 30 and the cap 27 (see Figs. 6 and 7) and of 105 such a circumferential extent as to fit between the flanges 30'. Those portions of the radial edges of the flange 30' which are adapted to be engaged by the projections 26^a, form seats for said projections to permit 110 longitudinal separation of the handle from the plug while compelling them to turn in unison when said projections are engaged by their seats. Those portions of the flanges 30' which fit under the flanges 27* 115 constitute the means for locking the handle against longitudinal movement. By turning the head 30 so as to bring it into the locked position, the plug 26 will be taken along so that the sealing plugs 36' will be brought 120 from the position shown in Fig. 8 to that shown in Figs. 11 and 17 and will positively seal the orifices of the tubes 38 and 39. The unlocking of the head 30 will of course uncover the ends of the tubes 38, 39, so that these tubes will be in registry with the passage 26', 26'', 26*. While I have shown in the drawings two plugs 36, 36', I desire it to be understood that the action of the plug 125 sealing the tube 39 is not material and that 130

it would be sufficient to provide a single plug having for its office the sealing of the tube 38. I prefer however to employ two plugs for the following reason: If only one plug is used, care will have to be exercised in assembling the apparatus to have this plug in the position of the plug 36 in Fig. 8, since if the plug were by mistake placed in the position of the plug 36' in Fig. 8, the outlet tube 38 would remain unsealed after the turning of the head 30 into the position shown in Fig. 11. When however two plugs are used, it does not matter how the parts are placed in assembling, since one or the other of the plugs will be sure to come into the position sealing the tube 38.

The location of the pump and its operating handle to one side of the receptacle offers the advantage of affording a relatively large unobstructed chamber in which the intake tubes 49, 50 may swing (see Figs. 3 and 4). Furthermore, this arrangement enables me to locate the points about which the intake tubes swing, in the longitudinal central axis of the receptacle. The device for locking the handle against longitudinal movement is so arranged that in the locked position (Fig. 10) the handle proper 32 will extend transversely, as shown in Fig. 16 (that is to say, the handle proper will be perpendicular to a plane containing the axes of the receptacle and of the pump). The handle proper will therefore in the locked position stand so as to make it easy to suspend the device against a wall say by means of a double hook 70 engaging the undersurface of the handle proper at each side of the shank 32'. When, as shown in Fig. 16, the ends of the handle proper in the said locked position project beyond the outline of the receptacle, I secure the further advantage of preventing or hindering the rolling of the receptacle if kept in a horizontal position in a tool box or the like.

Instead of combining the automatic air inlet with the filling cap, I may admit the air to the interior of the receptacle through the handle and piston rod, as has been shown in Fig. 17. For this purpose the piston rod, which in this case must be hollow, communicates with the outside air through the head 30 and has at its upper end an internal screw thread 63 adapted to receive a valve seat 64 with a spring-pressed valve 65 opening toward the interior of the piston rod. The lower portion of the piston rod is likewise screw-threaded internally to receive a suitable packing 66 surrounding a stationary tube 67, the lower end of which is secured to the plug 25'' and communicates with the inner space of the receptacle through a channel 25* in said plug. The plug 25'' is exactly the same as the plug 25 shown in the main form of my invention, except for the provision of the channel 25*.

The operation of my improved liquid-projecting device is as follows:

With the parts in the position shown in Figs. 6, 7 and 9, the pump can be operated. The outward movement of the piston will exert suction in the lower chamber of the pump cylinder and draw liquid contained in the receptacle into said chamber through the tube 41, chamber 42'', passage 42*, tube 45, passage 46*, one of the chambers 46' or 46'', and its corresponding intake tube 49 or 50. The valve 47, 47' acting by gravity, the liquid will always be sucked in through that one of the tubes 49, 50 whose intake is at the lowest level, while the communication of the other tube to the channel 46* is closed by the corresponding valve member 47 or 47', so that the air in the upper part of the receptacle can never be sucked into the pump cylinder. In the unlikely event of the apparatus being held perfectly horizontal, both intake tubes 49, 50 will be open at the same time to the passage 46*, so that liquid will be drawn into the pump from both tubes, the free ends of which of course are both within the liquid in such case. The valve 43, 43' or 44, 44' of course will be open in the direction from which the sucking action is exerted, and simultaneously therewith, the pressure created in the chamber above the piston also tends to keep the other valve 44, 44', or 43, 43' respectively, closed. When the piston has reached its uppermost position and the space below it has been entirely filled with liquid, the return stroke of the piston will force this liquid out through the tube 39, valve 40' (which will be in the open position owing to the pressure exerted from below), into the compartment 26'' formed in the plug 26. As has been described above, the unlocking of the handle has brought the plugs 36, 36' which in the position of rest, with the handle locked, seal the ends of the tubes 38 and 39, into the position shown in Fig. 8, so that these tubes are in communication with each other through passage 26', 26'', 26*. The liquid will then be forced from the compartment 26'' through the passages 26* to the compartment 26', thence into the tube 38 and projected out of the receptacle through the narrow opening in the nozzle 25'. At the same time liquid will be sucked into the upper chamber of the pump cylinder through one of the intake tubes 49 or 50, the valve casing 46, tube 45, valve casing 42 and tube 41, the valve member 44' during this stroke being pressed on its seat owing to the pressure created in the lower part of the cylinder, so that the liquid will pass from the tube 45 and channel 42* past the valve member 44' to the chamber 42' of the valve casing 42.

At the next outward stroke of the piston, the liquid which now fills the chamber of

- the cylinder between the piston 29 and the plug 26, will be forced into the passage 26', 26'', 26* through the openings 26^a, by lifting the U-shaped valve members 35.
- 5 Owing to the pressure thus created in the passage 26', 26'', 26*, the check valve 40 located in the tube 39 will be closed, so that the liquid will be forced through the tube 38 and ejected through the nozzle 25'.
- 10 During this outward stroke of the pump piston, the lower chamber of the pump cylinder will again be filled as described above, and the operation can be repeated as often as desired, or as long as there is any
- 15 liquid contained in the receptacle. During the inward stroke of the piston, the valve members 35 will be pressed down on their seats, so as to close the openings 26^a and to prevent any liquid passing through the passage 26'', 26' 26* from being sucked into the chamber of the pump cylinder between the plug 26 and the piston 29. As the liquid is expelled at each stroke, a corresponding volume of air will of course be
- 20 drawn in through the automatic valve 59 or 65.

In some cases it may be desirable to place the pump and connecting parts outside of the receptacle. This form of my invention has been illustrated in Figs. 18 and 19. All parts can readily be placed outside the receptacle, except the intake tubes 49, 50 and the valve casing 46 connecting them. These are of course arranged within the receptacle in the same way as described above in connection with the main form of my invention. The tube connecting the valve casing 46 with the valve casing 42 in this case extends through the wall of the receptacle and consists preferably of two parts 45', 45'' connected by a union 45*. All other parts are the same as in the other form and are preferably protected by a tube 68 surrounding them, this tube being secured to the receptacle by suitable clamping rings 69. The operation of this form of my invention is exactly the same as described above with regard to the main form.

50 The operation of my improved liquid-projecting device is very simple, while at the same time it is very effective. By a succession of quick in-and-out strokes I obtain a practically continuous stream of liquid issuing from the nozzle of the receptacle. The receptacle may be held and the pump operated in any desired position. The intake tubes are arranged in such a manner that the free end of at least one of them will practically always be immersed in the liquid.

While my device has been described in connection with a fire extinguisher and is primarily intended for such use, it may be adapted for other uses, such as for instance

for spraying liquids on plants, or for projecting a cleaning fluid on inaccessible parts of an automobile or other machine.

Various modifications may be made without departing from the nature of my invention as defined in the appended claims.

I claim:

1. In combination with a receptacle, a pump comprising a cylinder connected with the receptacle to withdraw liquid therefrom, said pump being provided with an outlet to discharge such liquid, a piston arranged to reciprocate in said cylinder, a handle for operating said piston, said handle being capable of turning relatively to the cylinder, a plug which is normally stationary and disconnected from the handle, said plug being arranged adjacent to said outlet and capable of turning relatively to the cylinder about the same axis as said handle, 75 a valve carried by said plug and controlling said outlet, and means for connecting said handle and plug so that they will turn in unison about the same axis.

2. In combination with a receptacle, a 90 pump comprising a cylinder connected with the receptacle to withdraw liquid therefrom, said pump being provided with an outlet to discharge such liquid, a piston arranged to reciprocate in said cylinder, a handle for operating said piston, said handle being capable of turning relatively to the cylinder, a plug which is normally stationary and disconnected from the handle, said plug being arranged adjacent to said outlet 95 and capable of turning relatively to the cylinder about the same axis as said handle but held against longitudinal movement, a valve carried by said plug and controlling said outlet, and means for connecting said handle and plug so that they will turn in unison about the same axis when the handle is pushed in fully.

3. In combination with a receptacle, a 110 pump comprising a piston, a cylinder in which said piston is arranged to reciprocate, and divided by said piston into two compartments, valved inlet connections from the receptacle to said compartments, said pump being further provided with an outlet to discharge the liquid withdrawn from the receptacle, a plug which is normally stationary and disconnected from the handle, said plug being arranged adjacent to said outlet, said plug containing a passage adapted to communicate with said outlet and having valved connections with said cylinder compartments, said plug being capable of turning relatively to the cylinder, but held against longitudinal movement, a valve carried by said plug and controlling said outlet, 115 and means for connecting said handle and plug so that they will turn in unison when the handle is pushed in fully.

4. In combination with a receptacle, a 130

- pump comprising a cylinder connected with the receptacle to withdraw liquid therefrom, said pump being provided with an outlet to discharge such liquid, a piston arranged to reciprocate in said cylinder, a handle for operating said piston, said handle being capable of turning relatively to the cylinder, a plug arranged adjacent to said outlet and capable of turning relatively to the cylinder about the axis of said cylinder but held against longitudinal movement, a valve carried by said plug and controlling said outlet, and means for connecting said handle and plug comprising projections on one of said parts and corresponding seats on the other part so arranged as to permit longitudinal separation of said parts while compelling them to turn in unison when said projections are engaged with their seats.
5. In combination with a receptacle, a pump comprising a cylinder connected with the receptacle to withdraw liquid therefrom, said pump being provided with an outlet to discharge such liquid, a piston arranged to reciprocate in said cylinder, a handle for operating said piston, said handle being capable of turning relatively to the cylinder, a plug arranged adjacent to said outlet and capable of turning relatively to the cylinder about the axis of said cylinder but held against longitudinal movement, a valve carried by said plug and controlling said outlet, means for connecting said handle and plug so that they will turn in unison when the handle is pushed in fully, and means operating when the handle is turned in one direction when fully pushed in, to lock said handle against longitudinal movement.
6. In combination with a receptacle, a pump comprising a cylinder connected with the receptacle to withdraw liquid therefrom, and provided with an outlet to discharge such liquid, a piston arranged to reciprocate in said cylinder, a handle for operating said piston, said handle being capable of turning relatively to the cylinder, and means, normally disconnected from the handle and mounted to turn relatively to the cylinder about the same axis as the handle, said means being brought into operation by turning the handle when it is in its innermost position, for closing the outlet of the pump and simultaneously locking the handle against longitudinal movement.
7. In combination with a receptacle, a pump comprising a cylinder connected with the receptacle to withdraw liquid therefrom, and provided with an outlet to discharge such liquid, a piston arranged to reciprocate in said cylinder, a handle for operating said piston, said handle being capable of turning relatively to the cylinder, means, normally disconnected from the handle and mounted to turn relatively to the cylinder about the same axis as the handle, said means being brought into operation by turning the handle when it is in its innermost position, to lock said handle against longitudinal movement.
8. In combination with a receptacle, a pump comprising a cylinder connected with the receptacle to withdraw liquid therefrom, said pump being provided with an outlet to discharge such liquid, a piston arranged to reciprocate in said cylinder, a handle for operating said piston, said handle being capable of turning relatively to the cylinder, and a plug which is mounted to turn relatively to the cylinder, in unison with said handle, and which closes the end of the pump cylinder nearest the handle, and a valve contained in said plug, said valve being adapted to be brought into operation by turning the handle and the plug when the former is in its innermost position, for sealing the outlet of the pump.
9. In combination with a receptacle, a pump comprising a cylinder connected with the receptacle to withdraw liquid therefrom, and provided with an outlet to discharge such liquid, a piston arranged to reciprocate in said cylinder, a handle for operating said piston, said handle being capable of turning relatively to the cylinder, means, normally disconnected from the handle and mounted to turn relatively to the cylinder about the same axis as the handle, said means being brought into operation by turning said handle when it is in its innermost position, for closing the outlet of the pump, and a stop for arresting the turning movement of the handle when it reaches said closing position.
10. In combination with a receptacle, a pump comprising a cylinder connected with the receptacle to withdraw liquid therefrom, said pump being provided with an outlet to discharge such liquid, a piston arranged to reciprocate in said cylinder, a handle for operating said piston, said handle being capable of turning relatively to the cylinder, a plug arranged adjacent to said outlet and capable of turning relatively to the cylinder but held against longitudinal movement, a valve carried by said plug and controlling said outlet, segmental projections extending lengthwise from the said plug toward the handle to engage seats on the latter when the handle is pushed in fully, and compel handle and plug to turn in unison, stationary segmental flanges coaxial with said projections, and segmental flanges on the handle to engage said stationary flanges when the handle is turned in one direction in its innermost position, to lock said handle against longitudinal movement.
11. In combination with a receptacle, a pump for discharging material contained in

- said receptacle, a valve casing located at the central portion of the receptacle, intake tubes leading from said casing toward opposite ends of the receptacle, connected valves 5 controlling the connection of the said valve casing with the intake tubes in such a manner that when one valve is closed, the other is open, another valve casing connected with the first-named valve casing, connections 10 leading from said second-named valve casing to the respective ends of the pump, and suction valves controlling the connection of the second-named valve casing with the respective ends of the pump.
12. In combination with a receptacle, a pump for discharging material contained in said receptacle, a casing connected with said pump, an intake tube located within said receptacle and provided at one end with a ball 15 engaging said casing, a perforated sliding member located within said casing, and a spring for pressing said member against the ball and the latter against the casing.
13. In combination with a receptacle, a pump located within said receptacle at one side thereof, for discharging material contained in said receptacle, an intake tube for said pump, arranged to swing in said receptacle, and a guide for said intake tube 20 acting as a stop to prevent said tube from reaching that part of the receptacle in which the pump is located.
14. In combination with a receptacle, a pump comprising a piston, a cylinder in which said piston is arranged to reciprocate, and divided by said piston into two compartments, valved inlet connections from the receptacle to said compartments, said pump being provided with an outlet to 25 discharge the liquid withdrawn from the receptacle, a plug in axial alignment with said cylinder and adjacent to said outlet, said plug having a passage adapted to communicate with said outlet and provided 30 with a port leading to the adjacent cylinder compartment, a valve movable lengthwise of the pump and controlling said port, and a valved connection through which the passage of said plug may communicate with 35 the other compartment of the pump cylinder.
15. In a syringe, the combination with a reservoir having an outlet, of a cylinder therein supported at opposite ends on the 40 reservoir, independently movable intakes for said cylinder, each intake being supported at one end, outlets at opposite ends of the cylinder, a channeled plug to connect said outlets to the reservoir outlet, and a piston to reciprocate in the cylinder.
16. In a syringe, the combination with a reservoir having an outlet, of a cylinder therein supported at opposite ends on the reservoir, a valve casing located substantially axially of said reservoir, movable in- 45
- takes for said cylinder, carried by said valve casing, said cylinder having outlets at its opposite ends, a channeled plug to connect said outlets to the reservoir outlet, and a piston to reciprocate in the cylinder.
17. In a liquid-projecting device, a fluid-receptacle, a piston-pump adapted to empty said receptacle, a handle for operating said pump, and a plug relatively to which said handle is adapted to reciprocate, said plug surrounding the pump piston rod and being adapted to open or close the outlet of the pump by being turned with and by the handle.
18. In a liquid-projecting device, a fluid-receptacle, a pump adapted to empty said receptacle, and comprising a piston, a handle to operate said piston, and a plug held against longitudinal motion but adapted to be turned about an axis in line with that of the piston by the turning of said handle to open or close the outlet of said pump.
19. In combination with a receptacle, a pump for discharging material contained in said receptacle, a casing connected with the pump, an intake tube located within said receptacle, and provided at one end with a ball one side of which engages said casing, and a yielding member engaging the other side of said ball.
20. In a liquid-projecting device, a fluid-receptacle of circular cross section having a transverse guide located therein at a distance from the center of the receptacle, a pump located within the receptacle on one side of said guide and provided with an operating handle extending to the outside of the receptacle, and a swinging intake tube connected with the suction port of said pump and located in the receptacle on the other side of said guide, and arranged to engage such guide.
21. In combination, a fluid reservoir, a cylinder pump with suction intakes located in said fluid reservoir to withdraw the fluid, one end of each intake being free to swing by gravity while the other is held in bearings near the center of the reservoir, valves controlling ports in a passage between said bearings, and valved connections between said passage and either end of the cylinder of the pump.
22. In combination, a fluid reservoir with independently swinging intakes having bearings for one end of each near the center and axis of the reservoir, valves between said bearings, and a piston pump adapted to force fluid at each stroke of its piston through said intakes to an outlet of the reservoir.
23. In combination, a fluid reservoir, a pump with movable intake tubes each having one end located substantially in alignment with the longitudinal axis of the reservoir, said ends being provided with bear- 55

- ing surfaces of spherical curvatures, yielding packing rings in contact with said surfaces; and connections from said intakes to the pump for ejecting the contents of said 6 reservoir.
24. In combination, a fluid reservoir, a pump mounted adjacent one side of the reservoir; suction intakes for said pump adapted to make contact by gravity with the 10 sides of the reservoir not occupied by the pump near each end thereof; valves controlling ports located between said intakes, and means to connect said ports with either end of said pump cylinder.
- 15 25. In combination, a fluid reservoir, a cylinder pump to eject the contents thereof, separately movable fluid intakes for said pump, located in said reservoir, gravity valves controlling said intakes, and valves movable 20 longitudinally of said pump, interposed between said intake valves and said pump.
26. In combination, a fluid-container, a double-acting fluid cylinder pump connected thereto, and adapted to discharge the 25 contents thereof, two intake gravity valves for said pump located substantially axially of the container, and a discharge outlet for said container located eccentrically to said container.
- 30 27. In a syringe, the combination with a reservoir having an outlet, of a cylinder located in said reservoir and connected immovably at opposite ends of the reservoir, a valve casing located substantially axially of 35 said reservoir; intakes for said cylinder supported at opposite ends of said casing; gravity valves in said casing, two suction valves which control passages leading to either end of said cylinder, a connection 40 leading from between said gravity valves to between said suction valves, a piston to reciprocate in said cylinder, and means to actuate said piston whereby fluid may be drawn from said reservoir and discharged 45 through its outlet.
28. In combination, a fluid-reservoir having an outlet, a double-acting fluid pump in said reservoir adapted to eject the contents thereof and comprising a cylinder stationary in said reservoir, a solid piston to reciprocate in said cylinder and a handle to operate said piston, and means controlled by said handle and located in axial alignment with said piston for closing the outlet of said reservoir.
- 50 29. A container, a double-acting fluid cylinder pump located in said container, connected thereto and adapted to discharge the contents thereof, in combination with two 55 intake gravity valves for said pump located substantially axially of said container.
30. In combination with a fluid-container, a double-acting cylinder pump adapted to expel the contents of said container, intakes 60 for said pump, adjacent each end of the 65 container; a valve casing located between said intakes and connected thereto, two gravity valves in said casing, another valve casing, a fluid-passage connecting the two valve casings, two suction valves contained 70 in the second-named valve casing, and fluid-passage connections from said suction-valve casing to each end of the cylinder of said pump.
31. In a syringe, the combination of a 75 tubular reservoir having an outlet; a pump cylinder in said reservoir; a piston to reciprocate in said cylinder; inlet ports to the cylinder at opposite sides of the piston; a passageway connected to the inlet ports of the cylinder and carrying suction inlet valves; intake means to said passageway having inlets from opposite ends of the reservoir and arranged to assume variable positions near the side of the reservoir; and 80 outlet ports from the cylinder at opposite sides of the piston connected to the reservoir outlet for the purpose specified.
32. In a syringe, the combination of a 85 reservoir having an outlet; a pump cylinder in said reservoir; a piston to reciprocate in said cylinder; inlet ports to the cylinder at opposite sides of the piston; a valve chamber connected to both of the inlets of the cylinder; valve mechanism in said chamber opening into and closing outward from the cylinder and operable to control the flow of liquid to opposite ends of the cylinder during the reciprocation of the piston; intake means to the valve chamber from opposite ends of the reservoir; valve mechanism to said inlet means operable to shut off said intake means from the liquid at one end of the reservoir when it is connected with the liquid at the opposite end; and valve controlled outlet ports from the cylinder at opposite sides of the piston connected to the outlet of the reservoir.
33. The combination with a fluid carrying reservoir, of a cylinder pump to extend 90 longitudinally of the reservoir and having suction inlets to opposite ends; a chamber to extend longitudinally of the pump connected to the suction inlets of the pump and having inlets to opposite ends; valve mechanism operable to shut off one inlet to such chamber when the other is open thereto; and a rigid intake tube for each end of said chamber loosely supported at one end by and connected to the corresponding chamber 95 inlet and the free ends adapted to assume variable positions near the side of the reservoir, and the free end of one tube adapted to assume variable positions near one end of the reservoir, and the free end of the other tube adapted to assume variable positions near the opposite end of the reservoir.
34. In a syringe the combination of a 100 reservoir; a piston chamber having a suction inlet and an outlet to the exterior of 105

- 120
- 125
- 130

the reservoir; a piston to reciprocate in control the flow of liquid to opposite ends of said chamber; and an intake tube connected to the suction inlet pivotally supported on an axis transverse to the axis of the piston 5 chamber, substantially as and for the purpose specified.

35. In a syringe, the combination of a tubular reservoir having an outlet; a pump cylinder in said reservoir; a piston to reciprocate in said cylinder; inlet ports to the cylinder at opposite sides of the piston; a chamber connected to both of the inlets of the cylinder; valve mechanism in said chamber arranged to open into and close outward from the cylinder and operable to 10 15

In testimony whereof I have signed this specification.

ALBERT V. SAMMIS.

Certificate of Correction.

It is hereby certified that the assignee in Letters Patent No. 1,532,443, granted April 7, 1925, upon the application of Albert V. Sammis, of Huntington, New York, for an improvement in "Liquid-Projecting Devices," was erroneously described and specified as "Fire Gun Manufacturing Company," whereas said assignee should have been described and specified as *Fire Gun Manufacturing Company, Inc.*, as shown by the records of assignments in this office; and that the said Letters Patent should be read with this correction therein that the same may conform to the record of the case in the Patent Office.

Signed and sealed this 15th day of December, A. D. 1925.

[SEAL.]

WM. A. KINNAN,
Acting Commissioner of Patents.
